GRIPPER FOR PLATEN PRINTING MACHINES.

No. 378,160.

Patented Feb. 21, 1888.

UNITED STATES PATENT OFFICE.

HENRY F. BECHMAN, OF CHICAGO, ILLINOIS, ASSIGNOR TO THE SCHNIED-WEND & LEE COMPANY, OF SAME PLACE.

GRIPPER FOR PLATEN PRINTING-MACHINES.

SPECIFICATION forming part of Letters Patent No. 378,160, dated February 21, 1888.

Application filed August 10, 1885. Renewed January 14, 1888. Serial No. 260,787. (No model.)

To all whom it may concern:

Be it known that I, HENRY F. BECHMAN, a citizen of the United States, residing in Chicago, county of Cook, and State of Illinois, 5 have invented certain new and useful Improvements in Grippers for Platen Printing-Machines, of which the following is a specification.

This invention relates to improvements in grippers for printing-presses, and more particularly to that class in which the grippers are automatically actuated by a cam to have an intermittent contact with the oscillating platen of the printing-press during a portion 15 of its backward and forward movement for holding the material being printed upon in the proper position to receive the impression, and therefore has no relation to that class in which spring-tension alone is depended upon 20 to hold the grippers in contact with the platen.

In the class to which my invention relates heretofore a rigid connection has been provided between the grippers and the gripper-cam; but such a construction is objectionable, owing 25 to the fact that the printing-space is thereby rendered difficult of measurement, because the grippers cannot be brought into contact with the platen, except when the latter is in an approximately vertical position and the rocking frame moved forward almost at the point of 30 making an impression, at which time the measurement can obviously be only imperfectly made, the marker being necessarily inserted between the platen and the rocking frame.

The prime object of this invention is to have 35 a flexible connection between the grippers and the gripper-cam, whereby the grippers may be brought into contact with the platen at any time during the operation of the machine.

Other objects are means for automatically 40 returning to and retaining the grippers in their normal position after being brought into contact with the platen, and to provide certain details of construction, hereinafter described, 45 and illustrated in the accompanying drawings, in which—

Figure 1 is a central vertical section through a printing-press, showing my device applied thereto; Fig. 2, an enlarged detail section 50 showing my device attached to the platen and engaging the gripper-cam; Fig. 3, a detail

plan view of the platen, showing my device attached and bent down in the position shown in dotted lines, Fig. 2; and Fig. 4, a modification of my improvement.

55

Similar letters of reference indicate the same parts in the several figures of the drawings.

A indicates the platen of an ordinary printing-press secured to the frame thereof, and caused to oscillate in the usual manner. Secured to either end, at the rear side of the platen, are the usual brackets, B, forming a support for the gripper-bar B', which is pivotally secured therein. This gripper-bar has the usual grippers, C, made adjustable by 60 means of slots D in gripper-bar and the screw-bolts E. Depending from the rear side, and near one end of the gripper-bar, is a lug, F, adapted to form a pivotal connection between said gripper-bar and a connecting-rod, G, which 65 lug also has a projection, F', adapted to strike against and form a stop to limit the outward movement of the spring actuated gripper-bar.

As before described, G is a connecting-rod 70 pivotally secured at its upper end to the lug F on the end of the said gripper-bar, and carrying on its lower end an anti-friction roller, H, which engages and travels in the gripper-camway I, for the purpose hereinafter described. Projecting rearwardly from the said 75 cam-lever near its upper end is an arm or hook, J, to which is secured one end of a spring, K, the other end of which spring is suitably secured at a convenient point to the stop F'.

By reference to Figs. 2 and 3 it will be seen 80 that the gripper-bar is eccentrically pivoted between the brackets B, as shown at a, and, as ordinarily occurs in printing-presses of this class, the grippers secured thereto are only designed to grip the material to be printed on just 85 at the moment the impression is made and release it immediately afterward, and are held free from contact therewith in order that the material may be removed and a blank sheet 90 substituted therefor.

In printing-presses as heretofore constructed, where a cam has been employed for operating the grippers, a rigid connection has been provided between the gripper and the gripper-cam, and in consequence of such connection the grippers have been held in a rigid 95 position at all times, and normally in approxi- 100

mately the position shown in Fig. 1, through the medium of said gripper-cam.

To make the necessary adjustment of the grippers for a new form of type accurate, it is necessary to continue the operation of the machine until the platen A attains approximately a vertical position, at which time the rocking frame L, carrying the type m, will have moved forward and be on the point of making an impression, and the space thus left between the platen and the type is so small that only a pencil or marker can be inserted between them; hence it is almost impossible for the operator to see in between the parts, and it becomes extremely difficult to make an exact adjustment of the grippers. To overcome these objections, I employ the devices and in substantially the manner about to be described. When the platen is in the position shown in Figs. 1 and 2 and the rocking frame is at the limit of its backward movement, the greatest degree of separation exists between the platen A and rocking frame, and the platen at this time is most easy of access and a measurement can be accurately made on its surface. Before the parts are moved to the position last described an impression is first made on a piece of paper suitably secured to the platen A, and the members then moved to the position shown in Fig. 1. At this point the operator grasps the end of one of the grippers and draws it forward and downwardly, for by reason of the flexible connection between the gripper-bar, to which the gripper is secured, and the gripper-cam the grippers are free to move if sufficient force is applied to overcome the tension of the spring K.

The grippers are bent down sufficiently to come in contact with the surface of the platen A, when the parts will assume the position shown by dotted lines in Fig. 2. In this position the parts are in the most convenient possible position for adjustment, and the grippers can be adjusted to the impression made on the blank with a nicety and exactness not possible to attain in a machine as heretofore constructed. After being adjusted, when released, the spring K will cause the grippers to resume their normal position, as shown by full lines, Fig. 2. The stop F' serves to prevent the spring K from throwing the grippers out of proper position.

It may here be observed that the gripper-cam is the usual cam employed for maintaining the grippers in their normal position during the oscillation of the platen A.

In the drawings, Fig. 3 represents the relative position of the platen and grippers when the latter are drawn down upon the platen for adjustment, and the dotted lines in same figure represent the outlines of an impression that has been made upon a blank sheet secured to the platen before adjusting the grippers.

It will be observed that by loosening the bolts E the grippers may be shifted and adjusted to exactly fit the impression or type-space required; and hence my device obviates the possibility of a faulty measurement in the printing-space, and hence a liability of destroying the outer rows of type.

It will be no departure from the spirit of my invention to dispense entirely with the actuating spring K, and instead thereof provide a spring-catch on the lever G, (see Fig. 4,) which will engage a suitable projection on the gripper-bar when the parts are in the same relative position as shown in Figs. 1 and 2. Of course when this connection is broken the grippers will lie upon the platen; but after the adjustment of the grippers is made the bars will be returned to their normal position, either by hand or by the continuous operation of the machine, and there caught and held by the spring-catch.

It is obvious that a measurement of the printing-space may take place at any time during the continuous operation of the machine.

Having described my invention, what I claim, and desire to secure by Letters Patent, is—

1. In a printing-press, the gripper-bar, a stationary cam, and an arm or rod pivoted to said bar and actuated by said cam, in combination with a flexible connection between said arm and the gripper-bar, substantially as and for the purpose described.

2. The platen and the gripper-bar pivotally secured thereto, and the adjustable grippers, in combination with the connecting-rod G, pivotally connected to said bar, the spring K, and gripper-cam I, substantially as described.

3. The grippers, the platen, the gripper-bar pivoted to said platen, in combination with the connecting-rod, and a pivot-connection between said rod and bar eccentric to the axis of the bar, substantially as described.

HENRY F. BECHMAN.
